UNITED STATES PATENT OFFICE.

GOTTFRIED FLÜCKIGER, OF ESCHERT, SWITZERLAND.

AUTOMATIC COUPLING FOR RAILWAY CARS.

Application filed November 26, 1923. Serial No. 677,009.

To all whom it may concern:

Be it known that I, GOTTFRIED FLÜCKIGER, a citizen of the Swiss Confederation, residing at Eschert, Switzerland, have invented 5 certain new and useful Improvements in Automatic Couplings for Railway Cars, of which the following is a specification.

This invention relates to an automatic coupling for railway cars with draw-hooks 10 and coupling links in which the draw-hook is arranged on a cranked pivot axle and securely maintained in the uncoupling position as well as in the coupling position, which latter it adopts automatically by locking 15 devices, one for each position. The one locking device is automatically released and the coupling is closed, the other coupling device having to be operated by hand for uncoupling and comprising means for bringing the draw-hook into the open position.

The invention will be best understood from a consideration of the following detailed description taken in connection with the accompanying drawings, forming a part 25 of this specification, with the understanding that while on the drawings one embodiment of the invention is disclosed, the invention is not confined to any strict conformity with the showing of the drawings, but may be 30 embodied in any manner which does not make a material departure from the salient features of the invention.

In the drawings:—

Figs. 1 and 2 show the coupling device 35 in longitudinal section at the open and closed position respectively.

Fig. 3 is a top plan view of Fig. 2.

In the drawings the draw-bar 2 is mounted in the end beam 1 of a railway 40 car so that it can move in vertical and horizontal direction. Buffer springs, not shown on the drawing, serve for elastically supporting the draw-bar in longitudinal direction. The draw bars 2 are 45 maintained in medium vertical position by means of supporting springs not shown on the drawing. The draw-bars 2 have each at the free front end a buffer casing 3 in which symmetrically to the vertical central plane 50 on the one side of this place a coupling link 4, adapted to oscillate in vertical direction and on the other side of the central plane a draw-hook 5 is arranged which is adapted to swing in the longitudinal direction of 55 said coupling link. A guiding funnel 6 under the coupling link is designed to re-

ceive a directing bolt 7 arranged under the draw-hook of the opposite coupling. The directing bolts 7 of the two parts of the coupling project from the end of the buffer casing and penetrate into the directing funnel of the opposite coupling part when two railway cars come in contact before the two buffer casings have come in contact, so that the buffer casings are mutually adjusted by 60 the parts 6 and 7. The draw-hook 5 is mounted on a horizontal cranked pivot axle 8 the cranked part of which is of such dimension that when the draw-hook is in the coupling position (Fig. 2) the horizontal central plane of the coupling link gripping over the draw hook and resting upon the cranked part of the pivot axle is situated in the horizontal central plane of the journals of the pivots. In alignment with the draw- 65 hook beyond the cranked part of the pivot axle an arm 9 is arranged which is bent towards the bottom of the buffer casing and has a weighted extension 10. By this weighted arm 9 the pivot axle 8 is main- 70 tained in a position in which the draw-hook adopts the coupling position. In this position the inner surface 11 of the draw-hook is inclined inwardly in upward direction towards a tongue 12 which is bent inwards 75 and downwards so that by this inner surface 11 and the curved tongue an automatic disengaging of the coupling link is absolutely 80 prevented. The draw-hook is maintained in the open position by a pawl 14 with heavy 85 head 13, said pawl engaging under a stud 15 laterally projecting from arm 9. This stud 15 when the arm 9 is swinging upward pushes back the pawl 14 which hangs in approximately vertical position owing to its 90 heavy head so that said pawl, as soon as the stud 15 has left the inclined back face of the pawl hook, swings under said stud 15. On the pawl 14 a rod 16 is hinged which is 95 cranked in upward direction and projects from the flange of the buffer casing. This rod 16 strikes directly before the closing of the coupling against the flange of the opposite buffer casing so that it is pushed back, whereby the pawl 14 is made to oscillate in- 100 wards away from stud 15. The arm 9 loses consequently its support and swings downward, whereby the pivot axle together with the draw hook is rotated from position Fig. 1 into the position Fig. 2. Upon the lower 110 surface of the buffer casing a pawl 18 is keyed on a shaft 17 which is parallel to the

pivot axle, said pawl 18 being situated in the same vertical plane as the draw-hook. The pawl 18 has a lateral arm 20 engaging under the nose 19 of the arm 9 of the draw hook. On the hub of the pawl which projects laterally from the buffer casing a two-armed lever 21—22 (Fig. 3) is mounted the free ends of which are bent in outward direction. The arm 21 of the lever is longer than the arm 22 so that the lever is overweighted towards the side of arm 20 and tends to turn through the intermediary of said arm 20 the pawl 18 towards the side of the draw-hook. The pawl 18 serves for holding the draw-hook in its coupling position and it grips for this purpose over the free end of the arm 9 which is in the lower end position. On the opposite end a shaft 17 projecting from the buffer casing of lever 23 is keyed which projects towards the other buffer casing. The free end of this lever 23 is slightly curved in upward direction and grips over the free end of the arm 21 of the opposite lever 21—22. A shaft 24 mounted in the beam 1 of the car serves for operating the pawl 18 in order to release the draw-hook. On the outer end of shaft 24 a lever 25 and on its inner end a lever 26 and a weighted lever 27 are mounted, the latter serving as counterweight for lever 26 so that the lever 26 is held in the position in which it is not in contact with lever arm 22. 28 is a nose which is arranged outside the pivot axle 8 in front of the draw-hook 5 and which serves for guiding, when the coupling is being closed, the hook. In order to enable that during the adoption of the improved railway car coupling the railway cars may be coupled by means of the actually used screw coupling a screw spindle 33 is suspended in the buffer casing to an eye 31 by means of a link 32, the buffer casing being provided with an aperture 30. This screw spindle carries a nut 35 with coupling link 34 and a lever 36 designed for rotating said screw spindle.

The operation and effect of the improved coupling for railway cars is as follows:—

In Fig. 1 the draw-hooks are shown in the open position and their backs 29 form the extension in upward direction of the inclined back of the nose 28. The rod 16 projects from the free end of the buffer casing and the pawl 18 is in the range of arm 9. The coupling link 4 projecting from the buffer casing rests in inclined position upon the upper edge of the directing funnel 6. For coupling two railway cars the cars are moved the one towards the other until the buffer bells come in contact. At this occasion first the directing bolts 7 penetrate into the directing funnels and adjust the two coupling parts accurately the one with regard to the other. The coupling links 4 slide over the noses 28

and the back 29 of the draw-hooks 5. As soon as the apex of the corresponding coupling hook has moved beyond the point of the corresponding draw hook the rods 16 are pushed back by the flanges of the opposite coupling casings, whereby the pawls 14 are brought under the studs 15. After this the arms 9 swing downward and make the pivot axles 8 with the draw hooks rotate so that the way in upward direction is bared for the coupling links. The draw-hooks are secured in their coupling position by the pawl 18.

To disengage the coupling the lever 25 is turned so that lever 26 makes the lever 22 move in downward direction. By the arm 21 the lever 23 of the other coupling member is at the same time turned in upward direction. The pawls 18 of the two coupling parts are consequently moved away from arms 9 which are now turned upwardly by the arms 20 so that the draw-hooks are rotated and the inner surfaces adopt an inclined position in outward direction. The coupling links can now slide over said draw hooks. The uncoupling can be effected during the travel easily even with the greatest admissible pulling as the coupling links engage with the draw-hooks in the horizontal plane of the pivot axle of said draw-hooks so that they tend neither to turn said draw-hooks in the one nor in the other direction. Only that power has consequently to be expended which is required for operating the locking pawls 18. As soon as the arms 9 are turned upwards by the arms 20 coming in contact with the noses 19 of said arms 9 the contact points of the coupling links get above the horizontal central plane of the pivot axles 8, whereupon the draw-hooks, when the uncoupling is done during the travel, are turned in the opening direction by the traction forces acting upon the same. The coupling links slide then over the inner outwardly inclined surfaces 11 of the draw hooks 5 whereupon the two coupling parts separate and the draw hooks are locked in the open position. The uncoupling can be effected from the side of the car.

I claim:—

1. An automatic coupling for railway cars comprising in combination a draw hook and a coupling link, a cranked pivot axle for the draw-hook, two locking devices for locking the draw hook in the open position and in the coupling position, means for bringing said draw hook automatically into the coupling position, means for releasing one of said locking devices automatically when the coupling is being closed, means for operating the other locking device by hand for opening the coupling, and means for bringing said draw-hook into the open position.

2. An automatic coupling for railway cars comprising in combination a draw-hook and

- a coupling link, a cranked pivot axle for the draw-hook, the crank of this pivot axle being of such dimensions that in the closed position of the draw-hook the coupling link resting upon said cranked part of the pivot axle is situated in the central plane of said pivot axle, two locking devices for locking the draw hook in the open position and in the coupling position, means for bringing said draw hook automatically into the coupling position, means for releasing one of said locking devices automatically when the coupling is being closed, means for operating the other locking device by hand for opening the coupling and means for bringing said draw-hook into the open position. 5
3. An automatic coupling for railway cars comprising in combination a buffer casing, a coupling link adapted to swing up and down arranged at one side of the vertical centre plane of said casing, a draw hook adapted to oscillate in the longitudinal direction of the coupling link and arranged at the other side of said vertical centre plane, a cranked pivot axle on which said draw-hook is keyed, a weighted arm on said pivot pin for maintaining said draw hook in the coupling position, and a pawl for locking said weighted arm in its position. 10
4. An automatic coupling for railway cars comprising in combination a buffer casing, a coupling link adapted to swing up and down arranged at one side of the vertical centre plane of said casing, a draw hook adapted to oscillate in the longitudinal direction of the coupling link and arranged at the other side of said vertical centre plane, a cranked pivot axle on which said draw-hook is keyed, a weighted arm on said pivot pin for maintaining said draw hook in the coupling position, and a pawl for locking said weighted arm in its position. 15
5. An automatic coupling for railway cars comprising in combination a buffer casing, a coupling link adapted to swing up and down arranged at one side of the vertical centre plane of said casing, a draw hook adapted to oscillate in the longitudinal direction of the coupling link and arranged at the other side of said vertical centre plane, a cranked pivot axle on which said draw-hook is keyed, a weighted arm on said pivot pin for maintaining said draw hook in the coupling position, a pawl for locking said weighted arm in its position, a shaft parallel to said pivot axle of the draw hook on which shaft said locking pawl is keyed, an arm of said shaft engaging under said weighted arm, a two-armed lever pivotally mounted on one of the ends of said shaft which project from the buffer casing said two-armed lever having outwardly bent ends, a lever on the opposite end of said shaft projecting from the buffer casing said lever projecting over one of the outwardly bent ends of the two-armed lever of the coupling member of the opposite car so that when one of said shafts is being rotated the shaft of the opposite coupling member is rotated also and the weighted arms of the cranked pivot axles of both coupling members are released by the locking pawls and make the corresponding draw-hooks adopt the open position. 20
